STOP MOTION FOR KNITTING MACHINES

Robert H. Lawson, Laconia, N. H., assignor to
 Scott & Williams, Incorporated, Laconia, N. H.,
 a corporation of Massachusetts

Application May 1, 1947, Serial No. 745,170

11 Claims. (Cl. 66—167)

1

This invention relates to a stop motion for a knitting machine, and more particularly a knitting machine in which the knitted fabric is wound upon a shaft. The invention is especially useful in connection with underwear knitting machines, to which use, however, it is not restricted.

In knitting machines making continuous fabrics such as tubular fabric for underwear, it is necessary to stop the machine periodically to remove the accumulated fabric. Such fabric is customarily rolled up as the knitting progresses and it has heretofore been known to determine the proper moment for stopping the machine by the size of the roll of accumulated fabric. It is important for subsequent operations such as dyeing that the amount of fabric in each successive roll be uniform, but automatic measurement of the roll diameter as a means of determining when the machine should be automatically stopped, have not proved wholly satisfactory. The measuring element tends to sink into the fabric and become inaccurate particularly when the fabric contains tuck or other fancy stitches. Also, the diameter and radial resistance of the rolls tend to vary giving rise to further inaccuracy.

I have now found that the weight of the roll may be employed to stop the machine and to insure that a uniform quantity of the knitted fabric will be removed with each roll. Thus subsequent operations upon each roll (as the dyeing operation) may be performed with certainty and with uniform results.

The invention is shown by way of illustration in its application to an underwear knitting machine in the accompanying drawings in which

Fig. 1 is a perspective view of the frame of a machine to which the invention is applied,

Fig. 2 is a broken front elevation of the apparatus illustrated in Fig. 1, and

Fig. 3 is an enlarged side elevation of the control apparatus employed.

In the embodiment of the invention which is illustrated in the drawings, there is shown the base 10 and legs 11 and 12 of an underwear knitting machine. In this the knitted fabric 13 extends downwardly to a pair of the usual fabric take-up rolls 14 and 15, between which it passes. Continuing thence, the fabric passes upwardly over a feeler bar 16 controlling the rate at which the fabric is wound upon the roll, in a manner forming no part of the present invention. Leaving the feeler bar, the fabric moves downwardly and is wound into a roll 17 upon a shaft 18. The shaft is carried by the two legs 11 and 12 of the knitting machine. The shaft 18 has a driven

2

end 19 supported upon the leg 11 by a bracket 20, and a cylindrical idler end 21 supported upon the leg 12 in a manner later to be described. The driven end of the shaft is square in cross-section, and its end fits loosely into a square recess axially formed in a bushing 22 on the end of a stub shaft 23 journaled in the bracket 20. The driven end of the shaft 18 is prevented from moving axially out of the socket in the bushing 22 by a collar 24 fixed to the shaft inside the support of the cylindrical idler end of the shaft. A gear 25 on the other end of the stub shaft meshes with a gear 26 upon the axle of a sprocket wheel 27. A sprocket chain 28, driven from the mechanism of the knitting machine, turns the sprocket wheel 27 and the meshing gears to roll up the knitted fabric upon the shaft 18.

The idler end 21 of the shaft 18 is supported from the leg 12 by a weighing apparatus which is best shown in Fig. 3. A bracket 29 is fixed to the leg 12 in any known or convenient manner. As here shown, a counterbalanced lever 30 is pivoted to the bracket 29 by means of a fulcrum screw 31 which passes through the lever and is fixed in the bracket 29. A notch 32 in the top of the short end of the lever 30 supports the idler end 21 of the shaft, which turns freely in the notch. An adjustable counter-weight 33 is slidably mounted upon the long end of the lever 30 and may be fixed in adjusted position thereon by means of a set screw 34. Thus, the weight of the shaft 18 and the roll 17 thereon tends to depress the short end of the lever 30 in which the notch 32 is formed, whereas the adjustable weight 33 tends to counteract the turning moment applied to the lever 30 by the weight of the shaft and roll.

When the knitted fabric begins to roll up on the shaft 18, the adjustable weight 33 overbalances the weight of the shaft and the roll, thereby causing the long end of the lever to bear upon a lower limit screw 35 turnable in a lug 36 formed on the bracket 29 and extending beneath the lever 30. As the knitted fabric is rolled upon the shaft 18 and the size and weight of the roll 17 increases, the moment about the fulcrum screw 31 in opposition to that of the adjustable weight 33 increases until finally the long end of the lever rises and comes to rest against an upper limit screw 37. This screw is threaded through an upper lug 38 which extends from the bracket 29 above the lever 30. It will be apparent that the lever is responsive to the weight of the knitted fabric on the shaft 18.

The distance of the adjustable weight 33 from the fulcrum screw 31 is set in such a way that the

lever 30 will rise and contact the upper limit screw 37 when the desired weight of knitted fabric has been rolled upon the shaft 18. At this point, it is desired to stop the machine in order that the roll 17 may be removed from the shaft 18 and a new quantity of fabric rolled thereon.

Various arrangements may be provided for stopping the machine when the lever 30 is overbalanced by the weight of the roll of fabric on the shaft 18. Such arrangements may include switches for opening or closing auxiliary circuits, latches which may be tripped by the lever, compound lever arrangements, and a variety of mechanisms well-known in the mechanical and electrical arts. Furthermore, such arrangements may be employed in obvious ways to stop knitting machines which are not electrically driven.

In the illustrative embodiment shown in the drawings, a micro-switch 39 is mounted upon the bracket 29 in such a way that the lever 30 will close the circuit through it when it rises to contact the upper limit screw 37. As here shown, an arm 40 extends from the micro-switch 39 to the top of the lever 30 between the fulcrum screw and the adjustable weight thereon; and the arm 40 bears upon the lever resiliently at all times. The construction of the micro-switch is such that when the lever 30 rises sufficiently to meet the upper limit screw 37, the arm 40 will close the circuit through the micro-switch. A wire 41 connects the micro-switch to the control box 42 of the machine; and the control box and the micro-switch are both grounded to the frame of the machine. Consequently, by closing the circuit through the micro-switch, it is possible to operate a stop motion either to break the circuit which operates the machine or to disengage the clutch of the machine.

Operation of the apparatus will be apparent. Having determined the amount of the knitted fabric to be periodically removed from the machine and hence its weight, the adjustable weight 33 is positioned upon the lever 30 so as to balance this weight exactly. The set screw 34 is next tightened to fix the position of the weight. The underwear knitting machine is then started through the control box 42 and the knitted fabric is rolled upon the shaft 18 until the predetermined weight is carried thereby. Thereupon, the lever 30 turns in a clockwise direction (as viewed in the drawings) about the fulcrum screw 31, closing the circuit through the micro-switch 39 and stopping the machine. The knitted fabric is then cut between the take-up roll 15 and the fabric roll 17. The fabric roll 17 is removed from the shaft 18 and the cut end of the fabric is fastened to the shaft. The underwear knitting machine is then started again, and the roll which has been removed from the shaft 18 is advanced to a succeeding operation. The loose driving fit between the square driven end 19 of the shaft 18 and the square recess in the bushing 22 permit the shaft to be easily removed and replaced. Furthermore, since the cylindrical idler end 21 of the shaft 18 merely rests in the notch 32 in the short end of the lever, the shaft 18 may be removed from the machine without disturbing the position of the collar 24 upon the shaft. The collar may, therefore, be permanently attached to the shaft.

Thus, the knitting machine is automatically stopped whenever a predetermined quantity of the knitted fabric has been accumulated. Each roll which is formed upon the shaft 18 is therefore of the same weight and size and may be

treated with confidence in identical manner in a succeeding operation.

The form of the invention here particularly described and illustrated is presented merely to indicate how the invention may be applied. Other forms and embodiments of the invention which come within the proper scope of the appended claims will, of course, suggest themselves to those skilled in the knitting machine art.

10. What is claimed is:

1. In a knitting machine, a shaft upon which the knitted fabric is rolled up, and a pivoted lever for stopping the machine supporting one end of the shaft, said lever being responsive solely to the weight of the knitted fabric on said shaft regardless of the size of the roll.
2. In an electrically controlled knitting machine, a shaft upon which the knitted fabric is rolled up, and a counterbalanced lever for affecting the operating electrical circuit of the machine to stop it, one end of said lever supporting one end of the shaft, said lever being responsive solely to the weight of the roll of knitted fabric on said shaft regardless of the size of the roll.
3. In an electrically controlled knitting machine, a shaft upon which the knitted fabric is rolled up, a lever supporting one end of said shaft responsive to the weight of the knitted fabric rolled thereon, and a normally open switch actuated by said lever to break the operating circuit of the machine.
4. In a knitting machine, a shaft for rolling and accumulating the knitted fabric, a drive from the main machine for rotating said shaft, a weighted lever supporting one end of said shaft, and a contact responsive to movement of said lever to disconnect the power supply of the machine.
5. In a knitting machine, a shaft for receiving and rolling the knitted fabric, parts driven electrically adapted to turn said shaft, a weighted lever supporting one end of said shaft, and a switch contact operable by said lever to break the electrical circuit of said electrically driven means when the weight of the said fabric on said shaft overbalances said weighted lever.
6. In a knitting machine, an electrical operating circuit, a shaft upon which the knitted fabric is rolled up, and a driving connection for said shaft operating through the machine from said electrical operating circuit, in combination with a pivoted lever supporting one end of said shaft, a normally open switch controlling said electrical operating circuit, and a mechanical connection between said switch and said lever for closing the circuit through said switch and stopping the machine when said lever is overbalanced by the weight on said shaft.
7. In a knitting machine, a shaft upon which the knitted fabric is rolled up, a driving connection for said shaft operated from the machine, and a pivoted counterbalanced lever for supporting one end of said shaft, in combination with a switch controlling the power supply of the machine, and a mechanical connection between said switch and said lever for closing said switch to stop the machine when said lever is overbalanced by the weight on said shaft.
8. In an electrically-driven knitting machine, a shaft, a driving connection from the machine for rotating said shaft and rolling knitted fabric thereupon, a pivoted lever supporting one end of said shaft, a counter-weight on said lever for overbalancing the weight of said shaft and the roll of knitted fabric thereon up to a critical

weight, and a normally open switch operable by said lever to stop the machine when the counter-weight thereon ceases to overbalance the weight of said shaft and the roll of knitted fabric thereon.

9. In an electrically-driven knitting machine, a shaft, a driving connection from the machine for rotating said shaft and rolling knitted fabric thereupon, a pivoted lever supporting one end of said shaft, an adjustable counter-weight on said lever for overbalancing the weight of said shaft and the roll of knitted fabric thereon up to a critical weight, and a switch operable by said lever to stop the machine when the counter-weight thereon ceases to overbalance the weight of said shaft and the roll of knitted fabric thereon, substantially as described.

10. A method of stopping a knitting machine in which knitted fabric is rolled up on a shaft supported at one end by a pivoted lever, comprising the steps of rolling up the fabric on the shaft without regard to the size of the roll and employing solely the weight of the roll to tip the lever, whereby the machine is stopped with a predetermined quantity of fabric on the shaft.

11. A method of stopping an electrically driven

15
10
15

6
knitting machine in which knitted fabric is rolled up on a shaft supported at one end by a pivoted lever, comprising the steps of employing parts driven by the said knitting machine to roll the fabric, and automatically breaking the electrical circuit when a predetermined weight of the fabric has been rolled by tipping the lever solely by the weight of the fabric, whereby the machine is stopped with a predetermined quantity of fabric

in the roll.
